UNITED STATES PATENT OFFICE.

JOHN M. MILLS, JR., OF TISKILWA, ILLINOIS, ASSIGNOR OF ONE-FOURTH TO HARRY L. MILLS, OF TISKILWA, ILLINOIS.

LADDER-SUPPORT.

1,115,559.

Specification of Letters Patent.

Patented Nov. 3, 1914.

Application filed June 17, 1913. Serial No. 774,223.

To all whom it may concern:

Be it known that I, JOHN M. MILLS, Jr., citizen of the United States, residing at Tiskilwa, in the county of Bureau and State 5 of Illinois, have invented certain new and useful Improvements in Ladder-Supports, of which the following is a specification.

This invention relates to ladder supports and has as its object to provide a support 10 and base which may be readily applied to any ordinary ladder and which will support the ladder in upright position so that one end of a board or scaffold plank may be supported upon any of its rungs.

15 It is one aim of the invention to provide a ladder support adapted to support a ladder in upright position and to extend at right angles from a wall against which it is braced, the support being adjustable 20 to permit of its ready application to and removal from ladders of various sizes.

Another aim of the invention is to provide a base adapted for application to any 25 ordinary ladder and adapted when applied to brace the ladder in spaced relation to a wall, or the like, and incidentally the invention aims to so construct the brace that it will prevent movement of the ladder toward the wall, its movement transversely of the 30 wall, and twisting.

Another feature of the invention resides in the provision of a bracing member designed for application to that rail of the ladder which is located next to the wall 35 when the ladder is in use, said brace preventing bending of the rail and serving also to a certain extent, to prevent vibration in the event that the ladders are relatively tall.

40 For a full understanding of the invention reference is to be had to the following description and accompanying drawing, in which:—

45 Figure 1 is a perspective view of the ladder support and brace embodying the present invention. Fig. 2 is a top plan view thereof. Fig. 3 is a detail front elevation of one rail of the ladder illustrating the manner of mounting the bracing beam 50 thereon. Fig. 4 is a detail perspective view of the upper end of the bracing beam and illustrating the clip. Fig. 5 is a group perspective view of the upper end portions of 55 the supporting standards, the parts connecting the same being shown separated but

in position to be assembled. Fig. 6 is a top plan view of the brace members for the supporting standards. Fig. 7 is a similar view but illustrating the members arranged in a manner different from that illustrated in Fig. 6. Fig. 8 is a vertical sectional view on the line 8—8 of Fig. 2. Fig. 9 is a perspective view of the structure shown in Fig. 8. Fig. 10 is a vertical transverse sectional view taken approximately on the line 10—10 of Fig. 1. Fig. 11 is a detail view illustrating a slight modification of the upper support. Fig. 12 is a view illustrating this support folded. Fig. 13 is a transverse sectional view through the support folded.

In the drawing the ladder to which the device is applied is illustrated as of the ordinary construction and includes the usual side rails 1 and connecting rungs 2. The ladder may be of any desired height, and as will be presently made apparent, the application thereto of the members embodying the present invention does not necessitate altering the construction of the ladder.

The support for the ladder is illustrated 80 as consisting essentially of a pair of supporting standards indicated by the numeral 3. Eye-bolts 4 are secured through the upper ends of the standards and pivotally hung upon the eye-bolt of one of the standards is a link-plate 5 having a key-hole slot 6 formed in its free end. A similar plate 7 is pivotally hung upon the other eye-bolt and is provided with a head 8 which may be engaged through the key-hole slot 6 whereby to pivotally connect the upper ends of the standards, and to afford a saddle for one of the lower rungs of the ladders, as clearly shown in Figs. 1 and 2. It will be understood, of course, that the link-plates 5 and 7 engage beneath the rung at the end of the same where it joins the rail and that consequently the said plates rest against the inner side of the rail. In order to securely connect the supporting standards with the rail, means is provided for connecting the standards rearwardly of their eye-bolts 4 and at such distance from the said bolts that the rail of the ladder may fit between the plates 5 and 7 and the last mentioned 95 connecting means, which will now be described. Both of the members of the connection just mentioned are preferably formed from strap-iron or bar metal and one of the members indicated specifically

100

105

110

by the numeral 9, is bent at a point between its ends to provide an attaching portion, this said portion being formed at its free end with a spur 11 which may be driven 5 into the standard 3 to which the said portion 10 is to be secured. A bolt 12 is fitted through an opening 13 formed in the attaching portion 10 and through an opening 14 formed in the respective standard and 10 the other wing or portion of the said member 9 is formed with a series of slots 15, the said series extending longitudinally of the said portion. The other member of the connection includes an attaching portion 16 15 formed with an opening 17 through which may be passed a bolt 18 corresponding to the bolt 12. The portion of this member, indicated specifically at 19 is reduced in width at its free end and has its reduced 20 portion struck down as at 20 so as to form a hook or lug engageable interchangeably in the slots 15, in the manner clearly illustrated in Fig. 2 of the drawings. The free end of the portion 16 is also provided with 25 a spur which corresponds to the spur 11 and which is indicated by the numeral 21 and is to be driven into the other one of the standards 3 in the same manner as the spur 11. In spacing the lower ends of the standards 3, a rod 22 is provided, the rod being pivoted at one end as at 23 to one of the standards and having its other end hooked and engaged in an eye 24 upon the other standard. At this point it will be understood 30 that the standards may be separated upon the link plates 5 and 7 as a pivot so that they will be located a greater or less distance apart at their lower ends and may therefore be adapted to afford a greater or 35 less length of bearing surface depending upon the height of the latter and it will be understood that after adjustment of the standards upon their connecting link plates, the connection 9 is to be adjusted by engaging the hook end or lug 20 and member 19 in one or another of the slots 15. It will be apparent by reference to Figs. 1 and 2 of the drawings that the members of the connection 9 rest against the outer face of the 40 rail of the ladder so that the rail is embraced on all sides. By reason of this fact the ladder is to a greater or less extent held against turning or twisting with relation to the support.

55 In order that the supporting standards 3 may be braced adjacent their lower ends with respect to the ladder, there is provided a means which is best shown in Figs. 6 and 7 of the drawings. The means mentioned 60 consists of two brace members, each formed from a single length of rod metal and indicated one by the numeral 25 and the other by the numeral 26. The members 25 and 26 are pivotally connected at one end to each 65 of the standards 3, as indicated by the nu-

meral 27. The member 25 at a point adjacent its free end is bent to form a laterally extending open-sided loop 28 and the extremity of this member is bent to form a hook 29. The member 26 adjacent its free 70 end is also bent to form an open-sided loop 30 which projects in the direction of the loop 28. The extremity of the member 26 is formed with an eye 31. Where the supporting device is to be used in connection 75 with a relatively narrow ladder or where it is desirable to locate the ground-engaging ends of the standards adjacent to the ladder, the hooks 28 and 30 are inter-engaged, as clearly shown in Fig. 6 of the drawings so 80 that their sides which are located next adjacent the pivoted ends of the members 25 and 26 will engage against the outer side of that rail of the ladder opposite the rail to which the upper ends of the supporting 85 standards are connected.

If the ladder in connection with which the device is to be used is however, relatively wide, or if it is desired to have the lower ends of the supporting standards engage the 90 ground a considerable distance from the ladder, the hook 29 is engaged with the eye 31, in the manner clearly shown in Fig. 7 of the drawings. In order that the members may be supported or prevented from dropping down upon the ladder, one or the other of the members is provided with a hook 32 which may have pivotal movement 95 thereon and which may also slide.

In order to brace the upper end of the 100 ladder with respect to the wall adjacent which it is to be supported, there is provided a bracing means which will now be described.

The bracing means mentioned above includes two arms 33 which, as illustrated in Figs. 1, 2 and 9 of the drawings, extend at an angle with respect to each other and these arms at their adjacent ends are fitted within clips 34 which have their connecting 105 portions 35 overlapped, as illustrated in Fig. 10 of the drawings and held at adjustment by means of a bolt and nut 36 passing through slots 37 formed in the said portions. It will be observed that the arms at their 110 said ends together with the connecting portions of the clips 34 straddle a rung of the ladder, which rung may either be the next to the top one or any one below the same.

In order that the bracing arms 33 may be 115 braced against that rung immediately above the rung with which their adjacent ends are engaged, there is provided a brace such as shown in Figs. 8 and 9 of the drawings. This brace consists of a cross-piece 38 and a 120 cross-piece 39, the latter being secured to one edge of the former and occupying a plane at right angles to the plane thereof. The cross-piece 39 at its ends projects beyond the ends 125 of the piece 38 and the said projecting ends 130

of the piece 39 are disposed, in assembling the brace with the arms 33, upon the upper edges of the said arms in the manner clearly shown in the said Figs. 8 and 9. In order 5 to hold the arms against the ends of the piece 38 the brace is provided at its ends with stirrups each formed from a suitable length of bar-metal secured at one end to the respective end of the cross-piece 39 and extending 10 downwardly therefrom to form a portion 40 which is parallel to the plane occupied by the end-edge of the cross-piece 38. At their lower ends the portions 40 are turned or bent inwardly at right angles as 15 at 41 and secured to the under edge of the cross-piece 38. It will be observed that the upper ends of the portions 40 of the stirrups are secured to the cross-piece 39 at diametrically opposite corners thereof, thus not only 20 strengthening the engagement of the stirrups with the arms 33 but adding also to the strength of the connection between the members 38 and 39. In order that the engagement 25 of the cross-piece 39 with the rung of the ladder may be a firm one, one edge of the cross-piece is notched or cut-away as indicated at 42 to partly embrace the rung in the manner shown in Figs. 1 and 8 of the drawings. The outer or remote ends of the 30 arms 33 are properly spaced by means of a cross-rod 43.

In order that that rail of the ladder which is to be positioned next adjacent the wall may be braced against twisting or bending 35 in all directions, there is provided a bracing beam which is indicated at 44. This beam is of nearly the same length as the ladder rail and adjacent its upper and lower ends is recessed, as indicated at 45, the said recesses being relatively shallow and receiving 40 the body portions of the clips, of which there are two, one being indicated by the numeral 46 and the other by the numeral 47.

The clip 46 is secured in place by means of 45 a bolt 48 fitted therethrough and through the recessed portion of the bracing beam 44. Both clips are preferably formed from bar-metal and the one indicated at 46 is bent at the ends of its body portion to form ends 50 49 which terminate in angularly extending portions 50 located parallel to the portion 46. The upper one of the portions 50 is of a length to engage over one of the rungs of the ladder in the manner shown in Figs. 1 55 and 3 of the drawings after the clip has been engaged about the rail, it being observed that the clip as a whole is pivotally mounted or swiveled so that it may be turned to position to be disposed against the rail 60 and then swung upon its securing bolt 48 to bring its ends into engagement with the forward and rear edges of the rail. The other clip indicated at 47 is of substantially the same construction as the one just described 65 and the corresponding parts are indicated

by corresponding reference numerals. The clip 47 has its portions 50 of the same length and neither portion is intended to be engaged with the rungs of the ladder. It will be understood that the clips serve to hold 70 the bracing means 44 snugly against the rail of the ladder so as to prevent bending of this rail or its twisting to one side or the other.

From the foregoing description of the invention it will be seen that there is provided a very simple bracing device adaptable for application to any ordinary ladder and that this device will support two or more ladders in such position that a scaffold plank may 75 be disposed at its ends upon any two corresponding rungs of the ladders. It will further be apparent that not only may the device be readily and quickly moved from place to place in front of a wall but the scaffold board can be adjusted to almost level 80 within the limits of the heights of the ladders.

In that form of the upper support shown in Fig. 11 of the drawings, an adjustable brace member is provided in lieu of the rod 43, and this member consists of a rod 43' pivoted at one end as at 44' to one of the side members 33 and having its other end provided with a hook 45' engaging interchangeably in openings 46' formed in a bar 47' pivotally connected as at 48' to the other one of the brace members 33. By reference to Figs. 11 and 12 of the drawings, it will be seen that the upper support or brace may 90 be folded to compact form, the side members 33 being folded on the bolt 36 as a pivot so as to lie side by side as shown in the said figures and the spacing member shown in Fig. 9 having its member 38 received between the said side members 33 and its portion 39 resting against the upper edges of the said members. It will be observed by reference to Fig. 13 that the members 40 may be swung around so as to receive the side members 33 when the portion 38 of the bracing member is in position between the said side members. 100

From the foregoing, it will be apparent 110 that the support embodying the present invention is constructed and arranged to hold or support the ladder with the lower ends of stiles spaced above the ground surface. In other words, the ladder is suspended and it together with the lower support and upper brace members act in substantially the same manner and is braced with relation to the wall, as when an ordinary ladder is leaned against the wall. As a consequence 120 of such a construction and arrangement of parts, weight imposed upon the ladders, or more specifically upon the scaffold boards supported thereby will cause the structure as a whole to be more firmly braced against the wall. It will also be observed that the 130

scaffold board may be adjusted up or down without the necessity of descending to the ground, inasmuch as the one using the support may stand upon either of the ladders 5 while adjusting the said board. It will further be apparent that the structure can be assembled and set up while standing upon the ground and that, consequently, there is no need to climb to the roof or window ledges in order to arrange the support.

Having thus described the invention what is claimed as new is:—

1. A ladder support including bracing members, clips connecting the members at one end and engaged with the rung of the ladder to be supported, and means connecting the members adjacent said end and engageable beneath and arranged to support another of said rungs.
2. In a ladder support, bracing members, means connecting the members and provided with stirrups receiving the said members, said means constituting also a saddle to engage beneath and support a rung of the ladder; with the lower end of the ladder spaced above the surface upon which the support is disposed.
3. In a ladder support, spaced bracing members, means connecting the members and comprising relatively angularly disposed cross-pieces, the ends of one cross-piece projecting beyond the ends of the other cross-piece and arranged to engage with corresponding edges of the bracing members, 35 and stirrups secured to the end-edges of the first mentioned cross-piece and to one longitudinal edge of the other cross-piece and spaced from the ends of the last mentioned cross-piece whereby to receive and embrace 40 the said members.
4. In a ladder support, spaced bracing members, means connecting the members and comprising relatively angularly disposed cross-pieces, the ends of one cross-piece projecting beyond the ends of the other cross-piece and arranged to engage with corresponding edges of the bracing members, and stirrups secured to the end-edges of the first mentioned cross-piece and to one longitudinal edge of the other cross-piece and spaced 45 from the ends of the last mentioned cross-piece whereby to receive and embrace the said members, the first mentioned cross-piece being provided with a seat to receive a rung 50 of the ladder to be supported.
5. In a ladder support, spaced bracing members, means connecting the said members and comprising clips having overlapped connecting portions, and means adjustably connecting the said portions, the clips supporting the bracing members in position for the engagement therebetween of a rung of the ladder to be supported.
6. In a ladder support, bracing means arranged in spaced relation, rail engaging

means connecting the members adjacent one end, and saddle links pivoted to the members at their said end and separably connected and arranged to engage beneath and support a rung of the ladder to be supported.

7. In a ladder support, a bracing means arranged in spaced relation, rail engaging means connecting the members adjacent one end, and saddle links pivoted to the members at their said end and separably connected and arranged to engage beneath and support a rung of the ladder to be supported, one of the said links being provided with a slot and the other link being provided with a head engageable in the slot.

8. In a ladder support, bracing members, means connecting the members and including a member secured to one of the bracing members and provided with a series of sockets, and a member secured to the other bracing member and having a portion arranged to overlap the socketed portion of the first mentioned connecting member and provided with a terminal hook interchangeably engageable in the said sockets.

9. In a ladder support, spaced bracing members arranged for connection with one side of the ladder to be supported, and means bracing the said members with respect to the ladder and comprising rods pivotally connected one to each of the bracing members and having interengageable connecting portions spaced along their lengths and adapted for engagement with the ladder at its other side.

10. In a ladder support, spaced bracing members adapted for connection with the ladder to be supported at one side thereof, and means arranged to coöperate with the other side of the ladder whereby to brace the said members with respect to the ladder, the said means comprising rods pivotally connected one with each of the bracing members, the said rods being formed inwardly of their ends with open loops engaging with each other whereby to connect the rods at the points of location of the loops and the said rods being provided at their ends with other interengageable elements adapted to connect the ends at their ends.

11. A ladder supporting and bracing device including bracing members, means connecting the members and constituting a saddle for one of the rungs of the ladder to support the same clear of the surface upon which the device is disposed, and means carried by the members for engaging one rail of the ladder.

12. In a ladder support, supporting and bracing members for the upper and lower ends of the ladder, each having means for the engagement and support of one of the rungs of the ladder and one of the rails thereof.

13. The combination with a ladder to be

supported, of a supporting member removably connected with the ladder at its lower end and extending laterally and downwardly beyond one rail thereof and supporting the ladder clear of the surface upon which the support is disposed, and bracing means for the upper end of the ladder movably connected therewith and extending up-

wardly and laterally from the other rail of the ladder.

In testimony whereof I affix my signature in presence of two witnesses.
